(57) **CLAIM**

I claim the ornamental design for a faucet aerator body, as shown and described in the drawings.

DESCRIPTION

FIG. 1 is a perspective view of the faucet aerator body design attached to a faucet for illustrating its use;

FIG. 2 is a perspective view of the faucet aerator body design of FIG. 1 of this invention;

FIG. 3 is a side view in elevation of the faucet aerator body design of FIG. 2;

FIG. 4 is a top view of the faucet aerator body design of FIG. 2; and,

FIG. 5 is a bottom view of the faucet aerator body design of FIG. 2.

The broken line showing of a faucet arm in FIG. 1 is for illustrative purposes only and forms no part of the claimed design.
